UNITED STATES PATENT OFFICE.

WILLIAM WATTIE, OF WORCESTER, MASSACHUSETTS, ASSIGNOR TO CROMPTON & KNOWLES LOOM WORKS, A CORPORATION OF MASSACHUSETTS.

LOOM.

No. 872,035.

Specification of Letters Patent.

Patented Nov. 26, 1907.

Original application filed February 3, 1905. Serial No. 243,925. Divided and this application filed April 19, 1907.
Serial No. 369,069.

To all whom it may concern:

Be it known that I, WILLIAM WATTIE, a citizen of the United States, residing at Worcester, in the county of Worcester and 5 State of Massachusetts, have invented certain new and useful Improvements in Looms, of which the following is a specification.

My invention relates to looms, and more particularly to the filling beating up motion 10 for a loom, which motion is shown and described but not claimed in my application for a patent, Serial No. 243,925, of which this application is a division.

The object of my invention is to provide 15 an improved filling beating up motion for looms, adapted to be used on looms for weaving different classes of fabric.

In my improvements in filling beating up motion, I provide a series of blades, which 20 are preferably made separate, and provided with hubs, which are preferably fast on a rock shaft. The warp threads pass between the blades, which act as a reed to separate and guide the warps, and also act to beat up 25 the filling, after it is inserted in the shed. The blades are made so that they always extend through the warp threads, and above the warp threads in the upper plane of the shed, when said blades are in their extreme 30 backward position.

My invention consists in certain novel features of construction of my improvements as will be hereinafter fully described.

I have only shown in the drawing a detached portion of a loom, with my improvements in filling beating up motion combined therewith, sufficient to enable those skilled in the art to understand the construction and operation thereof.

40 Referring to the drawing:—Figure 1 is a sectional elevation of my filling beating up motion, taken at a point indicated by line 1, 1, Fig. 2, looking in the direction of arrow *a*, same figure, and, Fig. 2 is a section, on line 45 2, 2, Fig. 1, looking in the direction of arrow *b*, same figure; the harnesses are not shown in this figure.

In the accompanying drawing, 1 is a loom side or end frame, 2 are the harnesses, in this 50 instance four in number. 3 are the warps, which are threaded through the heddles in the harnesses, and pass over the roll 4 at the front of the breast beam 5.

I will now describe my improvements in 55 beating up motion.

A rock shaft 6 extends through the loom, in front of the harnesses, and is mounted in this instance at each end in suitable bearings 7, on stands 8 secured to the inner side of the loom frame. The shaft 6 has fast on 60 one end the hub 9' of an arm 9; the end of the arm 9 carries a pin 10 with which is pivotally connected the forked end 11' of a cam lever or arm 11; the other end 11'' of the cam lever or arm 11 is also made forked shaped or 65 slotted, to receive a driven shaft 12. The shaft 12 has fast thereon a cam 13, having a cam groove 13' in one face thereof, into which extends a roll 14 on a stud 15, carried on the cam lever or arm 11. Through the 70 rotation of the shaft 12 and the cam 13, and the engagement of the roll 14 with the cam groove 13' in said cam, and the movement of the cam lever 11, a rocking movement is communicated to the shaft 6 at regular pre- 75 determined intervals.

On the rock shaft 6 is mounted a series of blades 16 having hubs 16', which are preferably made of the same thickness as the blades themselves. Separate collars or disks 17 80 are in this instance mounted on the shaft 6, between the hubs 16' of the blades 16, to hold said blades at a proper distance apart to give a clearance for the warp threads 3 passing between said blades. The hubs 16' 85 of the blades 16 are preferably fast on the shaft 6, and may be attached to the shaft 6 in any suitable manner, in this instance they are attached by a key 6', see Fig. 1.

The blades 16 are preferably made of an- 90 gular shape, as shown, with their upper ends extending toward the front of the loom, and of such a length that they will extend through the warp threads, and above the warp threads in the upper plane of the shed, 95 when the blades 6 are in their extreme backward position, as shown by full lines in Fig. 1. The series of blades 16 act as an ordinary reed, to separate and guide the warp threads, and to beat up the filling thread 18, which 100 is inserted in the open shed in front of the blades 16, as shown in Fig. 1. The filling beating up blades 16 are of sufficient length to always extend above the warp threads, and never pass below the upper plane of the 105 shed, formed by the warp threads, and will always act to separate and guide the warp threads and prevent their becoming twisted or entangled.

The advantages of my improvements will 110

be readily appreciated by those skilled in the art. My improvements may be used on looms for weaving different classes of goods, particularly heavy goods, as cane, duck, etc.

5 It will be understood that the details of construction of my improvements may be varied if desired.

Having thus described my invention, what I claim as new and desire to secure by Letters Patent is:—

10 1. A filling beating up motion for a loom, comprising a shaft, and a series of filling beating up blades thereon, said blades having a rocking motion, and in their lowest position extending above the warps in the up-

per plane of the shed, to separate the same and form guides therefor.

2. A filling beating up motion for a loom, comprising a rock shaft, and a series of filling beating up blades fast thereon, said blades in their lowest position extending above the warps in the upper plane of the shed, to separate the same and form guides therefor, and means for positively moving said blades to beat up the filling. 20

WILLIAM WATTIE.
